CLAIM

The ornamental design for a remote control device, as shown and described.

DESCRIPTION

FIG. 1 is a front perspective view of a remote control device, showing a first embodiment of our new design;

FIG. 2 is a bottom perspective view showing the first embodiment of our new design;

FIG. 3 is a front view showing the first embodiment of our new design;

FIG. 4 is a rear view showing the first embodiment of our new design;

FIG. 5 is a right side view showing the first embodiment of our new design;

FIG. 6 is a left side view showing the first embodiment of our new design;

FIG. 7 is a top view showing the first embodiment of our new design;

FIG. 8 is a bottom view showing the first embodiment of our new design;

FIG. 9 is a front perspective view of a remote control device, showing a second embodiment of our new design;

FIG. 10 is a bottom perspective view showing the second embodiment of our new design;

FIG. 11 is a front view showing the second embodiment of our new design;

FIG. 12 is a rear view showing the second embodiment of our new design;

FIG. 13 is a right side view showing the second embodiment of our new design;

FIG. 14 is a left side view showing the second embodiment of our new design;

FIG. 15 is a top view showing the second embodiment of our new design; and,

FIG. 16 is a bottom view showing the second embodiment of our new design.

Note that the second embodiment of FIGS. 9-16 comprises the first embodiment of FIGS. 1-8 with an additional backing for the remote control device. As such, FIGS. 1-8 may

(Continued)

be used as part of the design of FIGS. 9-16 by including the additional backing of FIGS. 9-16 into the views in FIGS. 1-8.
